UNITED STATES PATENT OFFICE.

LEONARD GLOVER, CLARENCE GLOVER, AND DAVID CROWTHER, OF LEEDS, ENGLAND.

FIRE-BOX FOR LOCOMOTIVE-BOILERS.

SPECIFICATION forming part of Letters Patent No. 730,904, dated June 16, 1903.

Application filed November 1, 1902. Serial No. 129,702. (No model.)

To all whom it may concern:

Be it known that we, LEONARD GLOVER, CLARENCE GLOVER, and DAVID CROWTHER, subjects of the King of Great Britain and Ireland, and residents of Wortley, in the city of Leeds, England, have invented a certain new and useful Improvement in or in Connection with Fire-Boxes of Locomotive-Boilers and of Boilers of a Similar Type, (for which we have applied for patents in England, No. 8,134, bearing date April 8, 1902; in Germany, bearing date October 21, 1902; in France, No. 314,899, bearing date October 8, 1902, and in Belgium, No. 132,266, bearing date October 8, 1902,) of which the following is a specification.

The objects of this invention are to increase the steaming capacity of such boilers by increasing the heating-surface of the hot-
20 test part of the boiler and increasing the circulation of the water in the boiler and to reduce the wear and tear of the fire-box, thereby lengthening the life of the fire-box by protecting the longitudinal sides of the
25 fire-box from the full heat of the fire as well as by the increased circulation of the water down the water-space between these sides of the fire-box and the corresponding sides of the fire-box shell.

30 The above objects we attain by combining with such fire-boxes L-shaped or approximately L-shaped water-tubes having the vertical or approximately vertical limbs of adjoining tubes close or near to opposite sides of the fire-box, those of alternate tubes close or near to the same side of the fire-box, while the horizontal or approximately horizontal limbs run across the boiler and project into the water-space a short distance above the
35 40 foundation-ring on the sides opposite the vertical limbs, respectively, the upper ends of the vertical limbs projecting through the roof.

The invention is illustrated by the accompanying drawings, to which reference is had in the following description.

45 Figure 1 is a longitudinal section, and Fig. 2 a cross-section, of a locomotive fire-box constructed in accordance with our invention. Fig. 3 is a longitudinal section showing the arrangement of our invention whereby a greater ratio of the air-inlet space to the total

grate area can be obtained than given by the arrangement shown in Fig. 1. Fig. 4 is a cross-section of a special arrangement of the horizontal limbs. Fig. 5 is a detail plan view 55 of the grate-bar *g*.

a and *a'* *b* and *b'* indicate the L-shaped water-tubes, *a* and *a'* being the vertical or approximately vertical limbs and *b* and *b'* being the horizontal or approximately horizontal limbs 60 of the same, respectively. The vertical limbs *a* are placed near or close to the longitudinal side of the fire-box (indicated by the reference-letter *c*) and the vertical limbs *a'* near to the side *c'*. The upper ends of the vertical 65 limbs are screwed on the outside and pass through the roof of the fire-box, (marked *d*.) They are secured in position by a taper ferrule *f*, provided with a six or eight sided collar and tapped on the inside, so as to screw 70 on the ends of the limbs and screwed on the outside, so as to screw into the roof-plate *d*. If the ferrule is to be screwed into position without altering the position to which the end of the limb has been adjusted, the threads 75 on the inside and on the outside of the ferrule will be of the same hand, while if the tube has to be drawn up into position the threads will be of opposite hand. The upper part of the limb may be slightly cranked, as 80 shown, either or both for the purpose of conveniently spacing them according to the position of the roof-supports and the radius of the curves joining the roof *d* and the sides *c* *c'*, or and for influencing the combustion in 85 the upper part of the fire-box. If preferred, the taper ferrule, screwed or not screwed, may be inserted from the top or water side of the fire-box.

The horizontal or approximately horizontal 90 limbs *b* and *b'* run transversely across the bottom of the fire-box at a level slightly higher than the top of the foundation-ring *e*, so that the end of any one horizontal limb passes through the fire-box side plate into the 95 water-space at the opposite side of the fire-box to the vertical limb of the same water-tube—that is, the ends of the limbs marked *b* are fitted through the lower part of the horizontal side *c'* and the ends of the limbs marked 100 *b'* through the bottom part of the side plate *c*, to which side plates the ends are secured

by tapped and screwed taper ferrules *f*, as already described for the upper ends of the vertical limbs. Alternate horizontal limbs thus have their ends fitted into the lower 5 part of the same side plate and adjoining horizontal limbs have their ends fitted into the lower part of opposite side plates.

The horizontal limbs serve as transverse grate-bars, forming either the whole or part 10 of the grate, according to the draft, character of the fuel, and combustion requirements.

If the ratio of air-space to the total grate area is too small, say, for the class of fuel and available force of the blast, this may be increased 15 by spacing the tubes farther apart and placing a thin grate-bar *g*, Fig. 1, between adjoining horizontal limbs to prevent the fuel falling through. As this arrangement, however, reduces the maximum number 20 of water-tubes which can be got in the fire-box, where it is desirable to retain the maximum number of water-tubes we arrange adjoining horizontal limbs at different levels, as shown in Fig 3, with transverse grate-bars 25 *g* between the horizontal limbs *b'*, forming the upper row. The same object is attained by cranking the horizontal limb of every water-tube, as illustrated by the cross-section, Fig. 4, so that Fig. 3 would also represent a 30 longitudinal section on line A B of Fig. 4. In this case the length of the intervening grate-bars *g* would be nearly half the inside width of the fire-box and the grate-bars would be widened out toward the fire - box sides, as 35 shown by the plan of such a grate-bar in Fig. 5.

A swing drop-grate *h* may be provided at the lower end of the grate-bar for the removal of the fire or ashes.

The number of water-tubes which according 40 to this invention can be got into the fire-box will depend on the area of air-space required by the fuel and the available blast-pressure and the space required to get at the hexagonal or eight-sided collars of the ferrules *f*, the maximum number being nearly equal to the available length of the fire-box sides, divided by the outside diameter of the water-tubes.

Where liquid fuel, such as petroleum, is used, we propose to duplicate the arrangement by putting a second series of the L-shaped water-tubes within the first—that is, the vertical limbs of the second series are placed somewhat farther away from the fire- 55 box sides and the horizontal limbs somewhat higher, though this arrangement does not increase the number of tubes which can be got inside the fire-box.

It will be evident that the above are not 60 separate inventions, but merely changes in the arrangement or form of parts of the invention called for by the varied conditions which obtain in connection with the use of the invention.

The advantages also are more or less self-evident. There is first a very great increase 65 in the heating-surface in the fire-box—that

is, at the hottest part of the boiler, where it is of the greatest use. The water is caused to circulate down the water-space between the fire-box and the fire-box shell and up the water-tubes, and this circulation is promoted where the water in the boiler has the greatest depth, and consequently the maximum circulating effect. So far as the inventors are aware 70 there has previously been no effective or proper provision for the circulation of the water in the water-space between the fire-box and the fire-box shell. Further, besides the protection which the water-tubes themselves afford to the longitudinal sides of the fire-box from the intense heat of the fire the circulation thus obtained tends to keep down the temperature of these sides, so that racking of the stay-bolts, leakage around the heads of the stay-bolts, and fracture of the stay-bolts and blistering and bellying of the side plates are all obviated or reduced to a minimum. Further, as adjoining vertical limbs are always at least one diameter's distance apart 80 and are not quite close against the fire-box sides efficient inspection of the stay-bolt heads is not hindered; also, as the water-tubes are free to expand no detrimental strain is thrown onto them or their connections to the fire-box plates.

We are aware that water-tube grate-bars have been previously used in locomotive fire-boxes and do not, therefore, make any general claim for such; and,

Having above fully described our invention, we declare that what we do claim as our invention, and desire to secure by Letters Patent, is—

1. A fire-box having a flat roof and a rectangular horizontal section, surrounded by a water-space which is closed at the bottom by a foundation-ring *e*, in combination with a series of L-shaped water-tubes inclosed therein, having their vertical limbs arranged alternately close to opposite longitudinal sides of the said box and their horizontal limbs extending across the fire-box, their ends projecting into the said water-space just above the said foundation - ring substantially as set forth.

2. In boilers of the locomotive type the combination with the roof-plate *d* and longitudinal sides *c c'* of the fire-box of L-shaped water-tubes *a b a' b'* and grate-bars *g* all substantially as set forth.

3. In boilers of the locomotive type the combination with the roof-plate *d* and longitudinal sides *c c'* of the fire-box of L-shaped water-tubes *a b a' b'* having the adjoining horizontal limbs at different levels and grate-bars *g* inserted between the horizontal limbs *b'* of the upper row substantially as set forth.
